UNITED STATES PATENT OFFICE.

TOM R. COLE, OF ROFF, OKLAHOMA.

COTTON-SEED-HULL-DELINTING MACHINE.

1,246,715.

Specification of Letters Patent.

Patented Nov. 13, 1917.

Application filed June 2, 1916. Serial No. 101,329.

To all whom it may concern:

Be it known that I, TOM R. COLE, a citizen of the United States, residing at Roff, in the county of Pontotoc and State of Oklahoma, have invented certain new and useful Improvements in Cotton-Seed-Hull-Delinting Machines of which the following is a specification.

This invention has relation to cotton-seed delinting machines, and the nature and objects thereof will be readily apparent to those skilled in the art to which it appertains in the light of the following explanation of the accompanying drawings, illustrating what I now believe to be the preferred embodiment, of mechanical expression of my invention, from among other forms and arrangements within the spirit thereof, and the scope of the appended claims.

However, an object of the invention is to provide a machine of the character described which includes a drum having an inner abrading surface which is formed of diagonal perforations to remove the lint from the hulls in a complete and efficacious manner.

Another object of the invention is to provide a cotton seed hull delinting machine having a drum, as mentioned above, and having an area of circular perforations through which the delinted hulls are ejected by means of rubbing surfaces movable in close relation to the perforated area.

In addition to the foregoing my invention comprehends improvements in the details of construction and arrangement of parts to be hereinafter described and particularly pointed out in the appended claims.

In the accompanying drawings in which similar and corresponding parts are designated by the same characters of reference throughout the several views in which they appear;

Figure 1, is a vertical longitudinal section taken through a cotton-seed hull delinting machine constructed after the manner of my invention.

Fig. 2, is a transverse section taken on the line 2—2 of Fig. 1.

Fig. 3, is a fragmentary view of a portion of the drum showing the circular perforations, and

Fig. 4, is a similar view illustrating the diagonal perforations.

After the major portion of the fibers have been removed from the cotton-seed during

their passage through the gin, there is found to be a mass of short fibers clinging to the hulls of the seeds which it is the object of this machine to remove. These short fibers when removed and collected are used to a great extent in the manufacture of nitrated cotton for which purpose the material is preferable to cotton having long fibers.

In machines of this type heretofore constructed the delinting process was slow and tedious and consequently the quantity of lint produced per unit time was small, which made the cost of the operation of the machine necessarily high. I propose therefore to provide a machine capable of delinting a large quantity of hulls in a short time, owing to the provision of a novel form of abrading surfaces against which the hulls are thrown by centrifugal force and engaged by rubbing surfaces movable at a high rate of speed.

With reference to the drawings 1 indicates an inner drum formed throughout its length with circumferential abrading formations 2, which abrading formations comprise diagonally disposed elongated perforations, parallel, and extended in the same direction. As a result of these formations and the relation one to another, the effect of thus forming the perforations is to define a number of broken, spiral grooves extended circumferentially of the drum and from end to end. The inner edges of the perforations are sharpened as at 4, and the objects thereof will be readily apparent as the description proceeds.

An outer drum 5 is provided for encompassing the inner drum to close the perforations therein, but is spaced from the discharge end of the inner drum, which discharge end is located at the right-hand side of the machine shown in Fig. 1. The circumferential area of the inner drum uncovered by the outer drum is provided with a plurality of circular perforations 6.

Plates 7 and 8 are located at the head end and discharge end respectively of the drum to form closures for the same to afford a support for the drum. The plates are centrally apertured to form bearings for the shaft 9 which extends longitudinally through the drum, and is also journaled at the discharge end of the drum in a bearing 10. A pulley 11 is fixed to the shaft between the bearing 10 and the end plate 8 whereby the shaft may be rotated, and a plurality of

collars 12 are fixed to the shaft, and correspond in number to the number of abrading formations, and are adapted to be retained in the several planes of the perforations. Arms 13 are formed with threaded terminals for engagement with internally threaded sockets in the collars 12, and the outer ends of the arms are formed with arcuate rubbing surfaces 14 which are disposed for rotation in close relation to the diagonal perforations. Thus it will be obvious that owing to the rotative adjustment afforded by the provision of the threaded connection between the arms and the collars, the rubbing members 14 may be disposed at any desired angle with relation to the angle of the diagonal perforations so as to obtain various degrees of delinting effects.

20 A collar 15 is fixed to the shaft adjacent the discharge end of the drum and is formed with radial arms, an arcuate rubbing surface 16 is formed at the outer ends of the arms for movement in close relation to the circular perforated area of the drum for a purpose which will be presently obvious.

25 An opening 17 is provided at the head end of the drum and at the outer portion thereof for connection with a hopper 18 having journaled therein an agitator shaft 19 and an agitator 20 mounted upon said shaft. Pulleys 21 and 22 are mounted for rotation upon the shafts 9 and 19 respectively and are connected for rotation in unison by means of a belt 23.

30 35 An opening 24 is provided in the head plate 7 for establishing connection between the interior of the drum and the atmosphere, and the extent of said opening is controlled by means of a movable plate 25. 40 The end plate 8 is likewise formed with an opening 26 which is adapted to be placed in connection with some form of an exhausting or vacuum machine to create a draft of air through the drum, the volume of air flowing through the drum being controllable by the plate 25 mentioned above.

45 In operation the hulls are fed into the hopper 18 from which they are discharged into the interior of the drum then having been set in motion, the hulls are then thrown against the inner surface of the drum by centrifugal force and abraded against the sharpened edges of the diagonal perforations owing to their engagement between the surface of the drum and the surface of the rubbing members 14. The lint is thus gradually and completely removed from the hulls. Owing to the spiral and diagonal relation of the perforations, the hulls are 50 gradually conveyed toward the discharge end of the drum, and upon reaching the area of circular perforations they are projected or forced through said perforations by contact with the rubbing members 16 mounted for rotation in close relation to the

said perforated area. During the operation of the machine the current of air passing through the drum conveys the particles of lint to a receptacle from which it is subsequently collected after a sufficient quantity 70 has accumulated.

It will be obvious that the delinting effect of the machine may be varied by adjusting the angle of the rubbing members 14 so as to provide a shearing action between the 75 edge of the members and the sharpened edges of the perforations, and the volume of air being passed through the drum may be likewise varied to correspond to the delinting of the machine and the speed at 80 which the shaft is rotated.

85 Various ways of constructing my invention to employ the principles involved will occur to those skilled in the mechanical arts, and I therefore reserve the right and privilege of changing the form of the details of construction or otherwise altering the arrangement of parts without departing from the spirit of the invention or the scope 90 of the appended claims.

Having thus described my invention what I claim as new and desire to secure by Letters Patent is:—

1. A cotton-seed hull delinting machine including in combination a drum having an inner abrading surface, a feeding opening provided at one end of said drum, a plurality of perforations provided at the other end of the drum, a central longitudinal shaft journaled for rotation within the 100 drum, rubbing surfaces movable with the shaft for co-action with the abrading surfaces, to abrade the lint from the hulls and to convey the delinted hulls toward the perforated end of the drum, a plurality of arms 105 mounted on the shaft for movement therewith adjacent said perforated end, arcuate members on the arm for movement in close relation to the perforated area of the drum to force the delinted hulls through said perforations, means for rotating the shaft and means for creating a draft of air through the drum to remove the lint therefrom.

2. A cotton-seed hull delinting machine including an inner drum provided with a 115 plurality of elongated, diagonally disposed perforations, and a plurality of circular perforations at one end of said drum, an outer drum encompassing the inner drum for covering the elongated perforations, a central 120 longitudinal shaft journaled for rotation within the inner drum, arms mounted on the shaft and having rubbing members for engaging the elongated perforations, arms mounted on the shaft and having rubbing 125 members for movement adjacent the circular perforated area, means for rotating the shaft, and means for creating a draft of air through the drum.

3. A cotton-seed hull delinting machine 130

including a drum having an inner abrading surface and a perforated area at its discharge end, plates at the head and discharge ends of the drum to close the same and to afford a support therefor, the head end plate having an air inlet opening, and the discharge end plate having an air and lint exit opening, means for controlling the passage of air through the inlet opening, a hopper 10 in communication with the interior of the drum at the head end, an agitator shaft and agitator journaled within the hopper, a central longitudinal shaft journaled for rotation within the drum, means for rotating 15 the agitator shaft from the drum shaft, arms mounted on the shaft and having rubbing members for co-action with the abrading surface of the drum, arms on the shaft and having rubbing members for co-action with the perforated area of the drum, and a pulley mounted on the shaft whereby said shaft, arms and correlated mechanism may be rotated.

20 In testimony whereof I affix my signature in presence of two witnesses.

TOM R. COLE.
